United States Patent Office.

CHARLES CROW, OF ONARGA, ILLINOIS.

Letters Patent No. 63,142, dated March 26, 1867.

IMPROVED SCAFFOLD.

The Schedule referred to in these Letters Patent and making part of the same.

TO ALL WHOM IT MAY CONCERN:

Be it known that I, CHARLES CROW, of Onarga, in the county of Iroquois, and State of Illinois, have invented a new and useful improvement in Elevating and Extension Scaffolds; and I do hereby declare that the following is a full, clear, and exact description of the construction and operation of the same, reference being had to the annexed drawings, and letters of reference marked thereon, making a part of this specification, in which—

Figure 1 is a perspective representation of my scaffold.

Figure 2 is an elevation of the jointed rack and pinion.

Figure 3 is a transverse section of the slides of one side of the machine.

The nature of my invention consists, first, in the use of jointed racks for supporting the scaffold frame, operated between jointed standards by means of pinions, so arranged in convenient positions that the racks can be elevated or lowered. By this means the scaffold can be run down much lower than if the racks were made each of a single piece, for the jointed parts can be turned outward as the racks are run down, thus allowing the scaffold to move a much greater distance than if the racks had no joints. Second, in supporting the jointed standards by means of sliding bars overlapping each other, and secured in such a manner as to allow the scaffold to be spread apart or shut together to suit the situation in which the scaffold is used. The whole construction comprises a portable scaffold, which can be mounted upon wheels, and conveyed to and from the place where work is to be done in much less time than is usually employed in building temporary scaffolds, or in suspending the common swinging platforms from the roofs of buildings. And further, the scaffold is suitable and safe for supporting both workmen and material when employed either in painting, plastering, sign-fastening, joiner-work, and in all other kinds of business where a suitable foundation is to be had and too great an elevation is not required.

A B represent the frames supporting the gearing E, and to which are attached the jointed standards F in a substantial manner, they also being supported by the horizontal ties G, which hold them parallel. H is the jointed racks, having the tongues J fitting into and running in the grooves K made in the sides of the standards F, for the purpose of guiding the rack, as it is run up and down, by means of the pinion E. I shows the joints in the rack, made for the purpose of allowing sections to be turned outward when the scaffold is lowered, as seen at fig. 2. By this means the platforms L can be lowered down far enough to obviate the necessity of a ladder for mounting up on to the top of it. And further, the scaffold is as strong as if the joints I were not in the rack, for the upper joint cannot pass above top of the standards F. It will be seen in the drawings that there are double racks and pinions at each end of the scaffold, and that the pinions are made fast to the shafts P, which have bearings attached to the top of the frames A B. V shows the upper sliding bars, which are attached to the upper end of the racks H, and support the platforms L. 2 shows slots made in the bars, through which the large-headed bolts 1 pass, holding the lap in such a manner that the bars can be drawn out or shut together when it is necessary to lengthen the scaffold when in use, or shorten it when conveying it from place to place. The lower bars U T are fitted together by means of rabbets, and overlap similar to those at the top, and can also be drawn out and shut together in the same manner. W shows joints made in the standards F, in order that the top of the standards may be removed when it is necessary to move the scaffold into a building, and in other cases where the standards would be too high.

Operation.

The platform L can be elevated or lowered by turning the crank Q attached to the shafts P, and can be held up by means of the falls S operating upon the ratchets R. The standards F can be drawn out or shut together by hand force without difficulty, so as to suit the nature of the work to be done.

Having thus fully described my device, what I claim as new, and desire to secure by Letters Patent of the United States, is—

1. The combination of the jointed rack H, jointed standards F, and bars v, when constructed to operate the platforms L, substantially as set forth.
2. The combination of the sliding bars T U V, platforms L, and frames A B, substantially as set forth.

CHARLES CROW.
